UNITED STATES PATENT OFFICE.

CHARLES JAMES ADOLPH DICK, OF LYSAKER, NORWAY.

INSTRUMENT FOR INDICATING AND RECORDING THE AIMING OF NAVAL GUNS AND FOR TESTING THE CORRECTNESS OF THE AIMING.

SPECIFICATION forming part of Letters Patent No. 729,290, dated May 26, 1903.

Application filed September 23, 1901. Serial No. 76,217. (No model.)

To all whom it may concern:

Be it known that I, CHARLES JAMES ADOLPH DICK, a subject of the King of England, and a resident of Lysaker, near Christiania, in the 5 Kingdom of Norway, have invented a new or improved instrument for indicating and recording the aiming of naval guns at the moment of firing or supposed firing, for testing the correctness or incorrectness of the 10 aiming, and for aiming such guns, of which the following is a specification.

The rolling and pitching motions experienced by a ship at sea make it exceedingly difficult for naval gunners to take correct 15 aim at a target or hostile vessel.

The subject of this invention is an instrument intended to be used mainly for training the gunners to overcome the above-mentioned difficulties without necessitating the 20 actual firing of the gun. For this purpose the direction and movement of the gun at the moment of firing with regard to the horizontal plane and the object aimed at are accurately recorded. One can thus after the gun 25 has been fired or is supposed to have been fired determine definitely the direction in which the gun was pointing and moving at the given moment. There can therefore be no difference of opinion as to whether the 30 gunner aimed correctly and whether the mark would presumably have been hit if the gun had actually been fired at that moment.

The invention consists of several marking devices lying continually in a horizontal 35 plane, which marking devices at the moment of firing mark their positions on a surface which moves with the ship, and consequently with the gun. On this surface the horizontal plane is already marked by a line, so as to 40 enable one to compare the position of the gun at the moment of firing with the horizontal plane.

By attaching a sighting apparatus, with 45 which aim is taken at the mark, the position of a marking device lying in the sighting-line with regard to a vertical plane situated parallel to the longitudinal axis of the gun is recorded, thus showing lateral deviations.

The addition of a sighting arrangement 50 allows of the instrument being also used for

aiming the gun. This contrivance does not affect its use for marking the position and movement of the gun relatively to the horizontal plane at the moment of firing or supposed firing.

In the accompanying drawings, Figure 1 is a top or plan view of a gun-sighting and aim-recording device made in accordance with my invention. Fig. 1^a is an enlarged section of part of said device. Fig. 2 is a transverse 60 section on the line A A, Fig. 1. Fig. 3 is a transverse section on the line B B, Fig. 1. Fig. 4 is a view showing the two elements of the sighting device, and Figs. 5 and 6 are views illustrating a special construction of 65 part of the recording devices.

The instrument, as shown, consists of a disk *a*, which turns freely inside a shell or casing *b* on a point *c* or on a ball-and-socket joint, and it is kept constantly in a horizontal position by the weight *d*, like the card of a ship's compass, thus being independent of the rolling and pitching of the ship. On one side of the disk there are several—for instance, three or five—marking devices which 70 are in the same plane with one another and with the point of suspension of the disk *a*. Suitable mechanism enables these marking devices to be pushed forward radially and drawn back again. The drawings show marking-points *e* attached to small pistons *f*, which move inside cylinders. These cylinders are connected by tubes *g* *h* with an india-rubber ball *i*. On compressing this ball the marking-points *e* are first forced outward by the 80 compressed air and on releasing the ball they are returned to their normal positions by springs or otherwise.

The disk *a* is supplied with two sights *m* *n*, which determine a vertical plane in which 85 also the center marking device and the point of support of the disk are situated. These sights are aimed at the mark. To enable this to be done, the disk *a* must be capable of being turned. This may be effected by the 90 help of a tube *h*, which is connected with the center of the disk *a* by a universal or other suitable joint or hinge *o*. This tube *h* can serve as a passage for leading the compressed air from the ball *i* to the marking devices. 95 100

The pins p , placed on either side of the tube h , enable one to turn the disk a by means of the tube h without affecting the horizontal position of the disk a .

5 The shell or casing b , inclosing the disk a , is connected with the gun-carriage, and therefore with the ship, all the movements of which it follows. The upper part of the said shell, as shown, is shaped spherically and concentrically with the point of suspension of the disk a ; but it may be cylindrical or of any other suitable shape. Opposite the marking-points e the said shell has connected with it a carrier for paper or other indication-receiving surface r .

10 The method of using the instrument for practising firing is as follows: On the aforesaid piece of paper r , inside the shell or casing b , a horizontal line is drawn with a vertical one cutting it. The vertical line and the center of the disk are in a plane which is set parallel to the longitudinal axis of the gun. The disk a , is now turned so that the sights $m n$ are in line with the mark. Now if the ship 15 is perfectly at rest and the different points retain their relative positions on operating the pneumatic device (for example, at the moment of firing) impressions are made by the marking-points e on the aforesaid paper r . A line connecting these impressions will correspond exactly with the horizontal line already traced on the paper r , and the mark made by the center-marking point, situated below the front sight n , on the disk a , will 20 fall on the point of intersection of the horizontal and vertical lines. If the relative positions of the different parts were not as above described, the shot would presumably not have hit the mark. It will be understood that 25 when the ship is under way the shell or casing b is continually moving on account of the motion of the ship, while the disk a remains horizontal.

If at the moment of firing the different 30 parts have not the right relative positions, then the line indicated by the marking-points e will not correspond with the horizontal line or the impression left by the center marking-point will not fall on the point of intersection of the horizontal and vertical lines. The 35 extent and nature of the deviation—that is to say, the distance and relative position of the center marking-point from and to the point of intersection of the lines on the paper and the angle formed by the marked line with the horizontal line—show how far and in which direction the position of the gun at the moment of firing deviated from the correct position. One can thus determine without 40 actually firing the gun whether the mark would presumably have been hit if the gun had been fired.

To best indicate the rolling and pitching of the ship, the outermost of the marking-points e may be in a line at right angles to the point e , which is in line with the longitudinal axis of the gun.

The necessary corrections for the speed of the ship itself, the speed at which the target or hostile ship is moving, and the allowance 45 for wind, &c., can easily be made by moving the paper, and consequently the vertical line thereon, to the right or left, as may be required.

The elevation at which the gun is laid is not 50 recorded by this instrument.

The instrument can also be used for aiming guns, as it reduces to a minimum the difficulty of taking careful aim when the ship is in motion in a sea. For this purpose a horizontal bar or wire s is attached to the disk a near the front sight n . On the shell or casing b of the instrument and opposite to this bar or wire s another bar or wire t is fixed, which when the ship, and consequently the 55 instrument, is at rest stands opposite to and in the same plane or parallel with the bar or wire s on the disk. The disk is now held either by means of the aforesaid tube h or otherwise, so that it cannot turn but still 60 always retains its horizontal position.

The sighting-line is set parallel to the vertical plane of the longitudinal axis of the gun with such allowance for the speed of the ship, &c., as may be necessary. The aiming is 65 done by the sights $m n$ on the disk a , and as soon as the two bars or wires, the one on the disk s and the other on the shell or casing t , are parallel and more or less close to one another the gun is fired. If the two bars or 70 wires s and t are not parallel, it shows that the gun is not at that moment in a suitable position for firing, and the gunner must therefore either allow for this in the sighting or he must wait until the motion of the ship brings 75 the two bars or wires parallel to one another.

The recording apparatus which marks the deviation from the horizontal is not affected by this arrangement. It can thus be accurately ascertained whether the above-mentioned conditions were fulfilled at the given moment.

The instrument may be modified in different ways. For example, the marking of the horizontal and vertical lines on the recording- 80 paper may be effected by means of points on the shell or casing or on the paper-carrier which leave marks on the paper. When after removing the paper these marks are connected by straight lines the horizontal and 85 vertical lines are indicated, and careful setting of the paper is thus rendered unnecessary. A cylindrical shape of the top of the shell or casing b , carrying the paper r , greatly facilitates this modus operandi, the error arising therefrom being but slight. Any other arrangement—for instance, an electric or mechanical—can be used instead of the pneumatic for actuating the marking devices.

Instead of placing the marking-points e on 90 the disk a and the recording-paper r on the casing b it is also possible to place these marking-points which may be substituted by any other marking device—for instance, by a wire

or by a colored pencil—on the casing *b* and the recording-paper on the disk *a*, which always remains in a horizontal position.

The instrument can also be fitted with a reflecting-mirror for indirectly observing the sighting-line.

The indication of the rising or falling of the ship and the gun at the moment of firing is important, as it may have a considerable influence on the correct firing of the gun. These motions can be indicated by two marking devices attached to the disk *a* at an angle of ninety degrees to one another, which at the moment of firing make impressions on a strip of paper fixed opposite to them. An arrangement which can be used for this purpose is shown in Figs. 5 and 6.

A marking-piston is fitted with a small roller *u*, around which an elastic or yielding thread *u* is wound, the ends of which are fastened at two points, one over the other, on the shell or casing *b*. The marking-piston has a second pointer *v* at the side of the usual central one *e*. When the part of the shell *b* opposite the piston rises relatively to that part of the horizontal disk *a*, the second marking-pointer *v* of the piston is turned upward, for instance. Two marks are thus made on the paper, and by their relative positions one can see in which direction the shell or casing *b* was moving at the moment of firing.

Suitable stops may be provided to limit the movement of the pointer *v* above or below a horizontal line passing through the pointer *e*. It is understood that these stops are so placed as to limit the motion of the small roller, so that almost immediately upon a change in the relative positions of the shell and the disk taking place motion of the roller will be stopped. As a result the elastic or yielding thread slips on the roller without turning it any more, although as soon as the direction of motion of the two above-mentioned parts is reversed the roller *U* is almost instantly turned in the opposite direction and brought to rest by striking the second stopping-pin. By making the distance between the two stopping-pins sufficiently small it is thus possible to make the point *v* take up its position almost immediately after the commencement of the reversal of the motion, and upon the projection of the piston carrying the two marking-points a record is made which will indicate whether the shell, and consequently the gun, was moving upwardly or downwardly when said record was made.

Having thus described my invention, I claim and desire to secure by Letters Patent—

60 1. In an apparatus for indicating and recording the aiming of naval guns, the combination of a recording-surface and a marker normally out of contact with the same, said elements being so mounted with respect to each other that one occupies a normally quiescent position and the other partakes of the movement of the ship, and means for bring-

ing the said marking device into contact with the recording-surface at will when the gun is supposed to have been fired, substantially as described.

2. In apparatus for indicating and recording the aiming of naval guns, the combination of two or more markers and a recording-surface so mounted in respect to each other that one occupies a normally quiescent position and the other partakes of the movement of the ship, said markers being disposed in the same plane, but at different angles, and means for bringing said markers into contact with the recording-surface at the supposed moment of firing, substantially as specified.

3. In apparatus for indicating and recording the aiming of naval guns, the combination of a recording-surface and a marker so mounted in respect to each other that one occupies a normally quiescent position and the other partakes of the movement of the ship, sighting devices carried by one of said parts, and means for reciprocating the marker and thereby bringing it into contact with the recording-surface at the supposed moment of firing, substantially as specified.

4. In apparatus for indicating and recording the aiming of naval guns, the combination of a recording-surface and a marker so mounted in respect to each other that one occupies a normally quiescent position and the other partakes of the movement of the ship, means for moving at will one of said elements circumferentially in respect to the other and means for bringing the marker into contact with the recording-surface at the supposed moment of firing, substantially as specified.

5. In apparatus for indicating and recording the aiming of naval guns, the combination of a recording-surface and a marker so mounted in respect to each other that one occupies a normally quiescent position and the other partakes of the movement of the ship, sighting devices carried by one of said members, means for moving one of said members circumferentially in respect to the other, and means for bringing the marker into contact with the recording-surface at the supposed moment of firing, substantially as specified.

6. In apparatus for indicating and recording the aiming of naval guns, the combination of a recording-surface and a marker so mounted in respect to each other that one occupies a normally quiescent position and the other partakes of the movement of the ship, means for bringing said marking device into contact with the recording-surface at the supposed moment of firing, and sighting devices carried in part by the normally quiescent member and in part by the movable member, substantially as specified.

7. In apparatus for indicating and recording the aiming of naval guns, the combination of a recording-surface and a marker so mounted in respect to each other that one occupies a normally quiescent position while the other partakes of the movement of the

- ship, said marker comprising two marking-points, one movable in respect to the other, means whereby the movement of the ship is caused to effect change in the relation of said marking-points, and means for bringing the marking-points into contact with the recording-surface at the supposed moment of firing, substantially as specified.
8. In apparatus for indicating and recording the aiming of naval guns, the combination of a recording-surface and a marker so mounted in respect to each other that one occupies a normally quiescent position and the other partakes of the movement of the ship, said marker being connected to the piston of a pneumatic projector, whereby it can be brought into contact with the recording-surface at the supposed moment of firing, substantially as specified.
9. In apparatus for indicating and recording the aiming of naval guns, the combination of a recording-surface and a marker so mounted in respect to each other that one occupies a normally quiescent position and the other partakes of the movement of the ship, a pneumatic projector carrying said marker and serving to bring the same into contact with the recording-surface at the supposed moment of firing, and an elastic bulb communicating with said pneumatic projector and supplying the motive fluid therefor, substantially as specified.
10. In apparatus for indicating and recording the aiming of naval guns, the combination of a recording-surface and a marker so mounted in respect to each other that one oc-

cupies a normally quiescent position and the other partakes of the movement of the ship, said marker comprising a rotatable disk having connection with the recording-surface, whereby it is rotated by reason of the movement of one of the parts in respect to the other, and said disk having also an axial pointer and a non-axial pointer, substantially as specified.

11. In apparatus for indicating and recording the aiming of naval guns, the combination of a casing containing a recording-surface and a weighted disk or plate so mounted in said casing as to maintain a normally horizontal position therein, one or more longitudinally-reciprocable markers carried by said disk or plate, and means for projecting said marker or markers into contact with the recording-surface, substantially as specified.

12. In apparatus for indicating and recording the aiming of naval guns, the combination of a disk or plate centrally mounted so as to normally maintain a horizontal position, a casing having a recording-surface concentric with the axis of said mounting, one or more markers carried by said disk or plate and means for projecting said marker or markers into contact with the recording-surface, substantially as specified.

In testimony whereof I have signed my name to this specification in the presence of two subscribing witnesses.

CHARLES JAMES ADOLPH DICK.
